(57) **CLAIM**

The ornamental design for a component for a hearing aid for the deaf, as shown and described.

DESCRIPTION

1. Component for a hearing aid for the deaf
Figure 1.1: is a perspective view of a component for a hearing aid for the deaf;
Figure 1.2: Perspective is a perspective view thereof;
Figure 1.3: Left is a left view thereof;
Figure 1.4: Front is a front view thereof; and
Figure 1.5: Bottom is a bottom view thereof.
The broken lines shown in FIGS. 1.2, 1.4, and 1.5 illustrate portions of the component for a hearing aid for the deaf that form no part of the claimed design.
